(57) **CLAIM**

The ornamental design for [an door for] a peritoneal dialysis
device, as shown and described.

DESCRIPTION

FIG. 1 is a front, top, and right side perspective view of a
first embodiment of the [door for a] peritoneal dialysis
device, [showing the new design] wherein the door is in a
closed position;

FIG. 2 is a front side elevational view thereof;

FIG. 3 is a rear side elevational view thereof;

FIG. 4 is a right side elevational view thereof;

FIG. 5 is a left side elevational view thereof;

FIG. 6 is a top plan view thereof;

FIG. 7 is a bottom plan view thereof;

FIG. 8 is [another] a front, top, and right side perspective
view [thereof] of a *second embodiment* of the peritoneal
dialysis device, [showing] wherein the door in an open
position;

FIG. 9 is [another] a front side elevational view thereof,
showing the door in an open position];

FIG. 10 is [another back] a rear side elevational view
thereof, showing the door in an open position];

FIG. 11 is [another left] a right side elevational view
thereof, showing the door in an open position];

FIG. 12 is [another right] a left side elevational view
thereof, showing the door in an open position];

FIG. 13 is [another] a top plan view thereof, showing the
door in an open position]; and,

FIG. 14 is [another] a bottom plan view thereof, showing
the door in an open position].

The broken lines represent unclaimed portions of the [door
for a] peritoneal dialysis device and form no part of the
claimed design.
